(57) **CLAIM**

The ornamental design for a combined card-holding and money clip device, as shown and described.

DESCRIPTION

FIG. 1 is a perspective view of the combined card-holding and money clip device showing my new design;

FIG. 2 is a front elevational view thereof;

FIG. 3 is a back elevational view thereof;

FIG. 4 top plan view thereof;

FIG. 5 is a bottom plan view thereof;

FIG. 6 is a right side elevational view; and,

FIG. 7 is a left side elevational view thereof.

It being understood that the broken lines are for illustrative purposes only and form no part of the claimed design.

1 Claim, 2 Drawing Sheets
